UNITED STATES PATENT OFFICE.

LUDWIG WOLFFGRAM, OF BROOKLYN, NEW YORK.

SEAMLESS-TUBE-FORMING MILL.

1,185,270.

Specification of Letters Patent.

Patented May 30, 1916.

Application filed July 1, 1915. Serial No. 37,609.

To all whom it may concern:

Be it known that I, LUDWIG WOLFFGRAM, a citizen of the German Empire, and a resident of New York, in the borough of Brooklyn, county of Kings, and State of New York, have invented certain new and useful Improvements in Seamless-Tube-Forming Mills, of which the following is a specification.

10 This invention relates to rollers for seamless tube forming mills, and has for its object to provide rollers specially positioned and configured to carry out a new mode of operation to be hereinafter more fully described.

An embodiment of such rollers is shown in the accompanying drawings, and will be more fully described hereinafter and finally pointed out in the claim.

20 In the accompanying drawing, Figure 1 is a diagrammatic view of one embodiment of this apparatus for rolling seamless tubes out of a solid mass, and Fig. 2 is a side view thereof, the upper roller being omitted. Fig. 25 3 represents an elevation of one of the side rollers, the upper roller, the plunger mandrel and the solid bar of metal in process of being tubulated.

Similar reference numerals indicate corresponding parts throughout the figures of the drawing.

In the embodiment of the invention herein shown two rollers 10 and 11 of different sizes are disposed side by side apart from each other and a third roller 16 is disposed between them above the center thereof. The side rollers 10 and 11 have their axes in parallel vertical planes, the axis of the roller 10 lying in the vertical plane $n-o$ and the axis of the roller 11 lying in the vertical plane $l-m$. The axis of the roller 10 is downwardly inclined to the horizontal from left to right as seen in Fig. 2 and the axis of the roller 11 is upwardly inclined to the horizontal from left to the right as shown in said figure. The axis of the smallest roller 16 lies in the horizontal plane indicated by the line $u-v$ and is inclined to the vertical planes aforesaid, said axis at one end lying in the vertical plane p and at the other end in the vertical plane q . The line 12-13 of Fig. 1 indicates the axis of the roller 11 and the line 14-15 indicates the axis of the roller 10 and the vertical plane passing through one axis is

parallel with the vertical plane passing through the other.

The upper roller 16, shown in Fig. 1, runs along loosely, in the well-known manner, during the rolling process and is arranged in horizontal bearings and lies in a certain angular position to the two vertical planes just referred to. By the entrance of the mass or block 17 of solid material out of which the seamless tube is to be formed between the rollers 16, 11 and 10, the block is so constricted that during the rotation of the rollers and the block, a truncated cone is formed. As a result of this, the formation of thin seamless tubes is possible. This is formed in connection with the plunger mandrel by the rotating roller surfaces of the three rollers. This cone, looked at in the imagination, passes through a line of the conical surface of the roller 11 nearest a similar line of the conical surface of the roller 10, and through that line of the conical surface of the upper roller nearest these first two, these lines constituting lines which form the tangents of the imaginary cone and the rollers 10, 11 and 16. Such a line of the roller 11 is seen in full view in Fig. 2, and is indicated by 20-21, and when this roller is rotated it forms the tangential line referred to. Such a line of the roller 10 is seen in full view in Fig. 2, as indicated by 24-25, and when this roller is rotated, it forms the tangential line referred to. This imaginary truncated cone has its base and upper surface in parallel planes, and, of course, this base and upper surface are of different sizes. The planes, passing through the base and the upper surface, are perpendicular to the vertical planes, passing through the axes of the rollers. In other words, the axis of the cone is horizontal. The plane, passing through the upper surface of the cone which is perpendicular to this axis of the cone, cuts the edges 22 and 27 of the rollers 11 and 10, and the projection of the cutting points 21^a and 25^a is shown at point 30 in Fig. 2. This plane cuts also the edge 29 at 29^a. By this the upper surface of the truncated cone is given a definite position, and thereby the position of the edges 27 and 22 and 29 of the rollers 10, 11 and 16 are determined in relation to each other. The other plane, which passes through the edge 23 of the roller 11, the edge 26 of the roller 10, and the edge 28 of the 110

roller 16, and forms the base of the truncated cone, cuts the edge 23 at 20°, cuts the edge 26 at 24°, and cuts the edge 28 at 28°.

Any imaginary cone which has a base, the circle of which passes through the points 20°, 24° and 28° and has the truncated upper surface with its circle passing through the points 21°, 25° and 29°, would have three lines forming part of the surface of this truncated cone, which lines would correspond to lines in the surfaces of the roller 11, roller 10, and roller 16. These corresponding lines are at the same time the tangential lines. I have considered an imaginary cone, or truncated cone, with the base larger than the truncated portion, and with the base forward of the truncated upper surface. In practice, the rollers 11, 10 and 16 are so arranged that the mass or blank 100 from which the seamless tube is to be formed, takes a position corresponding to this imaginary truncated cone, with the upper surface of the truncated cone, that is, the smaller diameter portion, contacting with the rounded head 51 of the mandrel 50. As then the mass or block, from which the seamless tube is to be formed, is moved forwardly by the rotating rollers, it is always tangential to the three rollers 11, 10 and 16 at three tangential lines, namely, 21°—20°, 25°—24°, and 29°—28°. By thus forming the mass or block of material with the smaller diameter portion of the conically shaped mass, continually abutting against the mandrel, very efficient and thin rolled tubes are capable of being produced.

Fig. 3 illustrates the development of a tube 200 out of a blank 100 by the aid of the mandrel 50 in connection with the rollers. The truncated cone surface of the side roller 11 between *h*—*i* coöperates with the corresponding large truncated cone of the side roller 10 and with the truncated cone of the upper roller 16 which lies between 29° and *c* and with the head 51 of the mandrel. The remaining cylindrical part *a* of the upper roller 16 between the parts *c*—*d*, serves to smooth the tube so formed. The efficiency of this process depends upon the relative angular positions described, by means of which the truncated cone is capable of being formed. It has been found that if these angular positions are changed, so that this truncated cone is not formed in the manner described, the mass, when it is rolled and rotated, is pressed too thin, and in consequence, a cutting action of the mass results. This disadvantageous feature, which has prevented heretofore the rolling of seamless tubes of thin walls, is entirely done away with by my improved positioning of the rollers in the manner described to form the imaginary cone and then have the mass shaped to conform to this imaginary cone.

65 The line 20—21 of roller 11, shown in Fig.

2, runs along the part 22—23 shown in Figs. 1 and 2; the line 24—25 of the roller 10 shown in Fig. 2, runs along the part 25—27 shown in Figs. 1 and 2; and the third tangent line runs along the part 28—29 of the roller 16 of Fig. 1.

In order that the block 17 be formed in in such a manner that its axis will be in a plane parallel to the two vertical planes referred to, through which the axes of the rollers 10 and 11 lie, the two side rollers 10 and 11 must have different shapes at their periphery. Therefore, the cross section at the end 24 of the roller 10 is smaller than in the cross section at the end 20 of the roller 11. The imaginary truncated cone touches therefore the roller 11 at the line 20°—21° of Fig. 1, the roller 10 at the line 24°—25° of Fig. 1, and the roller 16 at the line 28°—29°. The edge 29 of the upper roller 16 touches the imaginary truncated cone at 29° and the points 21°, 25° and 29° must lie in the same plane, which is perpendicular to the planes in which the axes of the rollers 10 and 11 are arranged, and the projections of the points 21° and 25° fall also together.

In general the side rollers are provided with one and the same form, and in this case, the projections of the edges 27 and 22 cut each other at the same point 30. It is therefore clear that it is necessary to roll above the line connecting the axes of the rollers 10 and 11, so that the block 17 cannot drop through. If, however, the cross sections at the edges 29 and 21 are the same in size, the block 17 will enter obliquely between the rollers. In this manner, it is possible to produce a good and above all thin rolled tube, which begins to develop at the edges 22, 27, 29, and at the points 21°, 25° and 29°. By suitably arranged adjustment of the three rollers, a conical member is formed out of the block between the three members, this member being greater or smaller depending on the relative position of the rollers, whereby a greater or smaller transporting velocity is attained.

As stated, the mandrel meets the upper surface of the truncated cone instead of the base, and by the differently sized side rollers placed in the position described, it is possible to produce very thin seamless tubes of copper, brass, etc., heretofore impossible with the means heretofore known.

I have shown one embodiment of my invention, but it is clear that changes may be made therein without departing from the spirit thereof as defined by the appended claim.

Having thus described my invention, I claim as new and desire to secure by Letters Patent—

In a rolling mill for rolling thin walled tubes, the combination of two coöoperating side rollers of different sizes disposed apart

from each other and having their axes in parallel vertical planes oppositely inclined to the horizontal, and a smaller roller disposed between said side rollers, above the centers thereof and having its axis in a horizontal plane inclined to the vertical planes passing through the upper end said side rollers, said rollers being relatively rotatable to form

between them an imaginary truncated cone tangent to each of the rollers. 10

In testimony that I claim the foregoing as my invention, I have signed my name in presence of a subscribing witness.

LUDWIG WOLFFGRAM.
